UNITED STATES PATENT OFFICE

2,173,185

ELEVATED BATHTUB

Samuel John Samelow Stanton, Chicago, Ill.

Application November 9, 1936, Serial No. 109,913

3 Claims. (Cl. 4—173)

This invention introduces a new facility for the modern bathroom. One purpose of the present invention is an economic grouping of bathroom fixtures. Several appurtenances are here 5 combined into a unit constituting a compactly integrated bathroom unit, which effects not only a saving of fixture material but also a saving of bathroom space.

Another purpose of the present invention is to 10 introduce for the bathroom interior architectural effects which so fascinate the builder of today—offsets, staggered conformations and streamlined bulk—a novelty which brings the bathroom feature of the home up to an advanced standard 15 of living accommodations.

Another purpose is easier access to the interior 20 of the bathtub, an access like that of the lavatory, which makes it possible for an attendant in a normal standing position to cleanse the walls 25 on the inside of the bathtub.

This bathroom facility may be manufactured in 25 enameled iron, Monel metal, or any other materials that can be used for bathroom fixtures.

Other novel features of this invention will be- 30 come quite obvious or will suggest themselves for contemplation as this invention is further disclosed hereinafter in words and figures and by the accompanying numbered illustrations which are made a part of this specification.

30 In the drawings, as figures:

Fig. 1 is a perspective view of my device.

Fig. 2 is a cross section taken on line 2—2 of Fig. 1.

Fig. 3 is a cross section taken on line 3—3 of Fig. 1.

35 Fig. 4 is a cross section taken on line 4—4 of Fig. 1.

The method of manufacturing this novelty will 40 from the herein included drawings be quite apparent to men skilled in the art of manufacturing bathroom fixtures. The present written description is intended merely to amplify the graphic presentation of the object for the record.

Referring to the drawings in detail.

45 The letter S indicates the invention as a whole. The height of it as herein scaled would be about the same as an office desk. The letter B shows the vessel part, being similar to the interior of the conventional bathtub, formed by the enclo- 50 sure of ordinarily four confluent upright walls embracing a floor wall 64 as a bottom. Two of these walls we may designate as end walls 12 and two as front and back walls 13. These four walls terminate in a rim 14, which may be confluent 55 with outside supporting walls like S, where the

inside vessel walls, 12, 13, 12, 13, are constructed on an inward slant.

The floor wall 64 is built in between the upright walls 12, 13, 12, 13 in a spaced relation with reference to the room floor F, for which the 5 novelty is intended. That is, this floor 64 is embodied with reference to its support S, at an elevation usually midway between the rim 14 and the bottom of the said support S.

The vessel being in an elevated position, step 10 means are included which may be used as treads for getting into and out of the vessel. These step means may be arranged in a formation to enable the user to rise into or descend from the vessel, or they may be integrations in the shape of useful 15 fixtures.

The letters L, WC and C indicate three such features. All of these are lower than the bathtub rim 14 and they may rest on the room floor 20 F on a level with the bottom of the bathtub support S.

In the present instance C, the clothes container, is a box-like structure, having surrounding walls 17, 18, 19 and 20. L indicates a lavatory. It is constructed like the conventional lavatory, 25 having surrounding walls 15, 21, 22 and 23.

WC indicates a water closet, constructed like the conventional water closet. The lavatory and the clothes container are of the same height merely for balance. The water closet may be incorporated between the other two fixtures. Wall 18 may be an extension of support S on one end of the unit. Similarly wall 21 may be an extension of wall S at the other end of the unit. Wall 16 may be a continuation of walls 35 15 and 17.

The water closet WC is lower than the other two fixtures. The three are integrated with the bathtub, either directly or by means of the support S, forming step means toward the top of the 40 bathtub B.

The support S need not be a continuous solid body, but may have indentations in accordance with the purpose of the designer. The numeral 24 indicates insets or indentations.

Numerals 60 shows a lid over the water closet hinged at 67. Numeral 66, Fig. 4, indicates a cross section of the wooden seat—with a hole in its center, usually used over the bowl of the water closet. It lies directly under the full cover 60. 50 This seat is hinged at 68. The numeral 69 represents the water closet bowl, which is connected to a water pipe as suggested by 70. The outlet for the lavatory L is suggested by the numeral 71.

The numeral 47 in Figures 3 and 4 indicates the 55

end walls of S. These may be omitted if other supports are available.

It will be noted that this unit requires no unusual plumbing connections. The fixtures in this 5 unit embody openings similar to openings in the conventional fixtures. The numeral 61, Fig. 2, indicates the outlet for the bathtub B contents, just as 70 suggests a water pipe for the bowl 69.

The unit can be installed in any bathroom under ordinary plumbing practices, just as it can be 10 manufactured in a well equipped plant under the present technique for building bathroom fixtures.

My invention herein, as it can readily be seen, is susceptible to various modifications and expansion in different directions. The details herein 15 shown are for purposes of disclosure and not as limitations. The right, therefore, is hereby reserved to make such variations or changes as properly fall within the scope of this specification, summarized in the appended formal claims.

I claim:

1. A bathroom fixture including a bathtub having side and end walls and a bottom wall, 20 said bottom wall being supported in substantially spaced relationship with the floor of the bath-

room and step means integrally associated with said bathtub and below the upper ends of said walls for easy access to the interior of said tub.

2. A bathroom fixture including a bathtub having side and end walls and a bottom wall, said bottom wall being supported in substantially spaced relationship with the floor of the bathroom, a washstand and water closet formed integrally with said bathtub below the upper ends of said bathtub walls, said wash stand and water closet being formed in stepped relationship with each other and with said bathtub for easy access to the interior of said tub.

3. A bathroom fixture including a bathtub having side and end walls and a bottom wall, said bottom wall being in substantially spaced relationship with the floor of said bathroom, one or more usual bathroom appurtenances formed integrally with said bathtub below the upper ends of said walls, said appurtenances being arranged in stepped relationship with the bathtub and the upper ends of said walls to afford easy access to the interior of said tub.

SAMUEL JOHN SAMELOW STANTON.
